UNITED STATES PATENT OFFICE.

J. HENRY BALLMAN, OF INDIANAPOLIS, INDIANA.

SCAFFOLD-BRACKET.

SPECIFICATION forming part of Letters Patent No. 328,999, dated October 27, 1885.

Application filed August 18, 1885. Serial No. 174,761. (No model.)

To all whom it may concern:

Be it known that I, J. HENRY BALLMAN, a citizen of the United States, residing at Indianapolis, in the county of Marion and State 5 of Indiana, have invented certain new and useful Improvements in Scaffold-Brackets, of which the following is a specification.

My invention relates to improvements in adjustable scaffold-brackets—such as are used 10 to form, in connection with ladders and a platform, movable scaffolds for painters or builders to work on; and the objects of my improvements are to provide an adjustable scaffold-bracket, stronger and more secure, and 15 one which will enable the workmen to build a higher scaffold with the same size ladders, than the ones now in use.

I attain these objects by the device illustrated in the accompanying drawings, in which 20 Figure 1 is a perspective view of my improved adjustable scaffold-bracket when supporting the platform from above, and Fig. 2 the same when supporting the platform from below.

Similar letters refer to similar parts throughout the several views.

a a are the steps of the ladder L.

B are the platform-supports. These supports are constructed in the following manner: An L-shaped flat iron bar, b, the short arm of 30 which terminates in a hook, b', is securely riveted to a similar bar, both together forming the T-shaped support B, which, with its hooks b' b', is hooked to one of the steps a of the ladder L.

35 The ends of the long arms of the bars b b are separated and a space left to receive the end of the brace C. This brace C is made out of flat iron, and is pivoted to and between the ends of the bars b b in such a manner that the 40 brace can be laid close onto the support B, either above or below the said support, and thus be used either as a suspending or a prop- ping brace to the support B. The support B being formed of two separate bars b b riveted together, and the brace C being pivoted to and between the ends of said bars b b, a strong bracket is obtained and the liability of accidents by breakage lessened.

The brace C is provided with a series of 50 holes, c c c, cut through the center of the bar. On the brace C slides up and down the double-hooked sleeve F. This sleeve F is secured

to the brace C at any desired point by a bolt or pin, p, extending through holes in the side plates of the sleeve F and one of the holes 55 c c c in the brace C. The sleeve F is made out of cast or wrought iron, and is provided with hooks f f, one projecting out and bending upward from the face and the other projecting out and bending downward from the rear plate 60 of the sleeve F. These hooks f f take hold of the steps a a of the ladder L, the face-hook being used when the brace C is supporting the platform G from below, as shown in Fig. 2, the rear hook being used when the brace C is 65 supporting the platform G from above, as shown in Fig. 1. To prevent the hooks f f from becoming disengaged from the steps a and causing accidents, I use thumb-screws h h, or any other suitable locking device, forming 70 a clamp under the steps a after the hook f is in place.

Having the hooked sleeve F adjustable on the brace C enables the operator to adjust the platform to any angle the ladder L may be 75 raised at.

By securing the sleeve F to the brace C by the pin p, and thus rigidly connecting the hook f to the brace C, all dangers of accidents that are liable to happen where a ratchet-bar 80 or a rack with a loop or ring, are used are avoided. By using the adjustable double- hooked sleeve F, and by pivoting the brace C to the support B, as described, I am enabled to support the platform G from below, using 85 the brace C as a prop. This makes it possible to raise the scaffold-platform to and hang the same to the uppermost step of the ladder L—an advantage over the scaffold-brackets now in use. The end piece of the brace C that extends beyond the pivot-point e 90 platform G is supported from b m slip¹ lock, and prevents the platform G from slipping off from the supports B B. The cle com²ews h h prevent the hooks b' b' from being accidentally disengaged from the ladder 95 ep a.

Having thus fully described my improvements, what I claim, and desire to secure by Letters Patent, is—

1. A scaffold-bracket having the support B, 100 formed of the two L-shaped bars b b, riveted together and provided with the hooks b' b', as described, the brace C, pivoted near its end to and between the ends of the bars b b, a series

of holes, *c c c*, cut through the center of the brace C, the adjustable sleeve F, sliding on the brace C, and provided with the double hooks *f f*, shaped and located as described, and the 5 bolt or pin *p*, forming means to secure the sleeve F to the brace C, all constructed as described, and for the purpose specified.

2. A scaffold-bracket having the supports B, formed of the two L-shaped bars *b b*, riveted together and terminating in the hooks *b' b'*, as described, the hooks *b' b'* being provided with the thumb screws or clamps *h h*, to keep the same securely on the steps *a* when desired, the brace C, pivoted near its end to and between the ends of the bars *b b*, a series of holes, 15 *c c c*, cut through the center of the brace C,

the adjustable sleeve F, sliding on the brace C, and provided with the double hooks *f f*, shaped and located as described, the thumb screws or clamps *h h* on said hooks *f f*, for holding the 20 same securely on the steps *a*, and the bolt or pin *p*, forming means to secure the sleeve F to the brace C, all constructed as described, and for the purpose specified.

In testimony whereof I have signed my name 25 to this specification in the presence of two subscribing witnesses.

J. HENRY BALLMANN.
